UNITED STATES PATENT OFFICE.

WILLIAM RAMM, OF KEMMA, NEBRASKA.

ANIMAL-CATCHER.

SPECIFICATION forming part of Letters Patent No. 320,167, dated June 16, 1885.

Application filed January 29, 1885. (No model.)

To all whom it may concern:

Be it known that I, WILLIAM RAMM, of Kemma, in the county of Knox and State of Nebraska, have invented a new and Improved 5 Animal-Catcher, of which the following is a full, clear, and exact description.

The object of my invention is to provide a simple, strong, inexpensive, and efficient device for catching animals—such as hogs—10 while they are running about the yard or pen or while standing.

The invention consists in an animal-catcher comprising a hook-head fixed to a suitable handle, a pivoted catch-lever provided with right-15 angularly-proportioned arms, and with a projection which locks into the teeth of a spring-pressed pawl when the catch-lever swings around to inclose the animal's leg between it and the hook-head of the device.

20 This invention consists, also, in particular constructions and combinations of parts of the animal-catcher, all as hereinafter fully described and claimed.

Reference is to be had to the accompanying 25 drawings, forming part of this specification, in which similar letters of reference indicate corresponding parts in both the figures.

Figure 1 is a side view of my improved animal-catcher with one side plate of the hook-head, catch-lever block, and handle removed; 30 and Fig. 2 is a back edge view of the catcher.

The letter A indicates the head of the animal-catcher, which is made of two bars or plates, *a a*, bent nearly at right angles and 35 connected at opposite ends by cross-pieces *a' a'*, so as to form an opening or slot, *a''*, between the plates *a a*, in which slot the catch-lever B and its locking-pawl C may work. The head A thus comprises a shank or body portion, 40 *A'*, and the hook-head portion *A''*.

The block D, in which the lever B and pawl C are pivoted, consists of two plates, *d d*, of about the same thickness as the plates *a a* of the head A, and connected to each other at 45 their outer ends by a guide-lug, *d'*, which projects into the slot *a''* of the shank *A'* of the head, and has a bolt end, *d''*, on which a thumb-nut, E, may be screwed to bind the block D firmly to the shank *A'* at any place desired. 50 I prefer to fix in block D a pin, F, which slides through a hole in an arm, G, projecting from

the shank *A'*, and serves as an additional guide and brace to the back end of the block, the forward end of which is held to the shank by a clevis or yoke, H, which is or may be 55 hung on the pin *b* by or on which the catch-lever B is pivoted to the block D between its plates *d d*.

As shown in Fig. 1, the catch-lever B has a right-angular general form comprising arms 60 *B' B''*, and is provided also with a projection, *B''*, the end of which is adapted to engage any one of a series of notches, *c*, formed in the edge of pawl C, which faces the catch-lever, said pawl being pivoted at *c'* to and between the 65 plates *d d* of block D, and having a projecting end, *c''*, forming a handle by which it may be swung back against the tension of a spring, J, which is hung on a cross pin, *j*, between the plates *d d*, and presses by its opposite ends or 70 arms on the lug *d'*, and the pawl to engage the pawl with the end *B''* of the catch-lever; but any other suitable spring may be used for this purpose.

K K are the opposite side plates or cheek-pieces of the handle L, which are fixed at the outer ends to the outer sides of the plates *a a* of head A, and extend diagonally at or across each face of the block D to brace it laterally, and project a suitable distance for the attachment of the handle L, which may be of any desired length.

In using the catcher the lever and pawl B C will be adjusted to the positions shown in full lines in Fig. 1, and the head A will be 85 held so that the leg of a running animal will enter between the cut-away outer end of the block D and the hook *A''* of the head, and so that the animal's leg will strike the arm *B'* of the catch-lever and swing the lever on its pivot 90 *b* to the position shown in dotted lines in Fig. 1, and as the lever swings forward its projection *B''* pushes back the pawl C and engages one of its teeth *c* to prevent the lever turning back, thereby securing the animal's leg between the hook end *A''* of the head A and the arm *B''* of the catch-lever.

The catcher may be used to seize standing animals by drawing it back by its handle to strike the arm *B'* of lever B against the animal's leg for operating the lever and its locking-pawl, as above described.

To adjust the catcher for use with larger or smaller animals, it is only necessary to loosen the nut E, and slide the block D along the shank A' and tighten the nut again, so that 5 the arm B', when it swings forward, will leave a larger or smaller space between it and the hook-head A' to accommodate the size of legs of different animals.

To remove the catcher from the animal's 10 leg, the pawl C is swung back by pressing or drawing on its end c², which leaves the catch-lever free to swing backward or open, as will readily be understood.

Having thus described my invention, I claim 15 as new and desire to secure by Letters Patent—

1. An animal-catcher comprising a hook-head, A, fixed to a suitable handle, a pivoted catch-lever, B, made with arms B' B² and projection B³, and a spring-pressed toothed pawl, 20 C, substantially as herein set forth.

2. An animal-catcher comprising a hook-head, A, fixed to a suitable handle, a catch-lever, B, made with arms B' B² and projection B³, and a spring-pressed toothed pawl, 25 C, said parts B C being pivoted to a block, D, adapted to slide along the shank of the head A, substantially as herein set forth.

3. An animal-catcher comprising a hook-head, A, fixed to a suitable handle, a catch-lever, B, made with arms B' B² and projection B³, and a spring-pressed toothed pawl, 30

C, said parts B C being pivoted to a block, D, adapted to slide along the shank of head A, in combination with the clevis or yoke H, and bolt and nut d² E, substantially as herein set 35 forth.

4. An animal-catcher comprising a hook-head, A, fixed to a suitable handle and formed of spaced and connected plates a a, a block, D, formed of plates d d, connected by a lug, d', 40 entering between the plates a a, and having a bolt end, d', the nut E, and yoke H, the catch-lever B, made with arms B' B² and projection B³, and the toothed spring-pressed pawl C, said parts B C being pivoted to the block D, 45 substantially as herein set forth.

5. The combination, in an animal-catcher, of the head A, fixed to a suitable handle and formed of spaced and connected plates a a, a block, D, formed of spaced plates d d, connected 50 by a lug, d', entering between the head-plates a a, and having a bolt end, d', the binding-screw E, yoke H, the pin F, entering a projection, G, the catch-lever B, made with arms B' B² and projection B³, and the toothed 55 spring-pressed pawl C, said parts B C being pivoted to and between the side plates, d d, of the block D, substantially as herein set forth.

WILLIAM RAMM.
